WINDOW GLASS INSULATION SYSTEM

Filed Aug. 29, 1934

By W. W. Williamson
Attorney.

UNITED STATES PATENT OFFICE

2,042,077

WINDOW GLASS INSULATION SYSTEM

Samuel A. Stoneback, Philadelphia, Pa.

Application August 29, 1934, Serial No. 741,891

5 Claims. (Cl. 20—56.5)

My invention relates to new and useful improvements in a window glass insulation system, and has for one of its objects to apply one or more additional panes of glass to a window sash or door to provide a dead air space or spaces which will act as insulation against a temperature on the outside of a building different from the temperature on the inside of the building.

Another object of my invention is to provide means for assembling one or more additional panes of glass on a stock door or window sash or ones that are now in use.

Another object of the present invention is to install one or more additional panes of glass on a window sash or door in a manner to make the joints about the additional pane or panes air tight.

A further object of the invention is to provide moulding for installing the additional pane or panes of glass, which moulding is grooved or chambered to receive and hold a suitable plastic composition to function as caulking means.

A still further object of my invention is the provision of a window glass insulation system applicable to new, stock and used doors and window sashes wherein one or more additional panes of glass are held in place by moulding attached to one or both faces of a door or window sash with the additional pane or panes in spaced parallel relation to the usual pane of glass whereby one or more dead air spaces are produced which function as heat insulation, said moulding carrying a plastic compound to caulk the joints and prevent leakage of air into and from the dead air spaces.

Still another object of the invention is to provide for sealing the joints of certain types of the regular panes of glass in doors or windows whenever it is necessary.

With the above and other objects in view, this invention consists of the details of construction and combination of elements hereinafter set forth and then specifically designated by the claims.

In order that those skilled in the art to which this invention appertains may understand how to make and use the same, I will describe its construction in detail, referring by numerals to the accompanying drawing forming a part of the application, in which:

Fig. 1 is a fragmentary broken view of a window sash illustrating one application of my invention.

Fig. 2 is a horizontal sectional view of Fig. 1.

Fig. 3 is a vertical section in the region of the meeting rails of two sashes equipped with that form of the invention illustrated in Figs. 1 and 2.

Fig. 4 is a view similar to Fig. 3, showing a modified form of moulding.

Fig. 5 is a sectional view illustrating the use of two additional panes of glass and showing one

of them inset for use in connection with double hung or sliding sashes, and

Fig. 6 is also a sectional view illustrating the use of two additional panes of glass, both on the faces of the sash and showing an alternate form 5 of moulding.

In carrying out my invention, 10 represents a frame included as a part of a door, window sash or the like, which is usually rabbeted, as at 11 to receive the regular or primary pane of glass 12, 10 held in place by suitable means 13, such as putty or moulding. In some instances one edge of the pane of glass 12 is merely set in a channel 14, Figs. 3 and 4 and often no sealing means is used.

By referring particularly to Figs. 1, 2 and 3, it 15 will be noted that an additional or secondary pane of glass 15 is placed directly against the face of the frame 10 so as to be disposed across the light opening and in spaced parallel relation to the primary pane of glass 12. Where the invention is used in connection with double hung or sliding window sashes said additional or secondary pane of glass is placed on the outside face 20 of the upper sash and on the inside face of the lower sash.

The additional or secondary pane of glass is held in place by moulding 16 which, in the particular form under consideration, is produced from metal fashioned to provide a lip 17, that overlaps the rim of the secondary pane, and a 30 flange 18 by which said moulding is secured to the frame with suitable fastening devices 19, such as screws. In the lip 17 is formed a longitudinal groove or chamber 20 for the reception of a plastic composition 21, such as caulking compound, 35 that seals the joint between the secondary pane of glass and the frame 18 and prevents leakage of air around said secondary pane.

By this arrangement of the two panes of glass, a dead air space 22 is formed that efficiently insulates one side of the frame from the other and prevents the passage of heat or cold, as the case may be, from the outside to the inside of a building. It also prevents the accumulation of moisture due to condensation and the resultant frost 45 during cold weather.

When two window sashes are double hung, so that one has to slide past the other, the secondary pane is placed on the outside face of the upper sash and on the inside face of the lower sash, 50 as illustrated in Fig. 3. In order to compensate for any "play" between the meeting rails of the sashes and seal the joint between said meeting rails, a suitable weather strip 23 is mounted at said joint.

In the application of my invention, whenever a sash is encountered in which the usual or primary pane of glass is installed by having one edge inserted in a channel, as shown in connection with the lower sash at 14 in Fig. 3, such pane 60

of glass is sealed by a sealing moulding 34. This moulding is similar to that previously described except that the lip is about a quarter of a circle instead of approximately a semicircle. The sealing moulding also holds a plastic composition 35.

I have illustrated the same invention in Fig. 4 to show the use of moulding produced from wood and therefore wherever identical parts are used they will be referred to by the same references numerals as previously employed. The mouldings are interchangeable and all metal or all wood or some metal and some wood ones can be used on the same installation.

As previously stated the secondary pane of glass 15 is placed against a face of the frame 10 and as shown in Fig. 4, moulding 24 produced from a strip of wood having any suitable or desirable configuration, is used to secure the secondary pane in position.

20 The moulding is particularly fashioned to provide a lip 25, that overlaps the rim of the secondary pane 15, and a flange 26 that engages the face of the frame about said secondary pane and through which fastening devices 27, such as 25 nails, are projected into the frame for attaching the moulding.

Within the lip 25 is formed a longitudinal groove or chamber to hold the plastic composition 28 for sealing the joint between the secondary pane and the frame. In addition to the groove or chamber in the lip, one or more longitudinal grooves or chambers 29 may be produced in the inner face of the flange to hold plastic composition to further insure an air tight seal about the 35 secondary pane of glass.

In the same manner as before outlined, the combination of the secondary pane with the primary pane produces the dead air space 22.

40 The reference numeral 30 indicates a sealing moulding for use in the same manner as the one shown at 34 in Fig. 3, but in this instance it is produced from a strip of wood with a longitudinal groove or chamber to hold the plastic composition 31 for making the primary pane air tight.

45 In Fig. 5, I have illustrated the same invention carried out to provide two dead air spaces 22a and 22b, and in this modification the primary pane of glass is installed in the usual or ordinary manner, then the secondary panes of glass 15 and 50 15a are assembled on the frame so that one secondary pane is on one side of the primary pane and the other secondary pane is on the opposite side of said primary pane.

55 One of the secondary panes, as 15, is mounted in the manner hereinbefore described and the other can be mounted in the same manner, as suggested by the showing in Fig. 6, to be later described, but when used in connection with double hung sashes one of the secondary panes must be inset sufficiently to eliminate any projections beyond one face of the sash. For this purpose the secondary pane 15a is shown as set in a rabbet 32 and held in place by glazing means 33, such as plain moulding, moulding holding the plastic composition as above described, putty or any equivalents.

60 As illustrated in Fig. 6, the two dead air spaces 22a and 22b are produced by the use of two secondary panes of glass 15 and 15a held in place on opposite faces of the frame 10 by moulding strips 24, which as illustrated are the same as shown in Fig. 4, but since the mouldings 16 and 24 are interchangeable, it will be obvious that the 70 moulding 16 can be used instead of the one shown.

This adaptation of the invention is particularly useful in connection with doors, casement windows or fixed frames.

From the foregoing it will be understood that I have provided a simple and inexpensive system or structural arrangement that makes it possible to readily insulate windows, doors and kindred objects without the necessity of manufacturing specially designed frames, so that the invention is applicable to present day windows and doors which are or have been in use as well as stock frames.

Of course I do not wish to be limited to the exact details of construction herein shown and described, as these may be varied within the scope 15 of the appended claims without departing from the spirit of my invention.

Having thus fully described my invention, what I claim as new and useful is:—

1. A frame having a primary pane of glass 20 therein, a secondary pane of glass placed against one face of said frame in spaced parallel relation to the primary pane to form a dead air space, a chambered moulding secured to the frame and overlapping the margins of the secondary pane, 25 and a plastic composition in the chamber of the moulding to make an air tight joint between the secondary pane and the frame.

2. A frame having a primary pane of glass 30 therein, a secondary pane of glass lying against a face of said frame in spaced parallel relation to the primary pane to form a dead air space, a moulding including a flange by which said moulding is secured to the frame and a lip overlapping the margins of said secondary pane to hold the latter in place and said lip having a longitudinal groove or chamber in its inner face, and a plastic composition in the chamber to seal and make an air tight joint between the frame and the secondary pane.

3. The structure in claim 2, wherein the flange of the moulding also has one or more longitudinal grooves or chambers in its inner face for the reception and retention of the plastic composition.

4. The combination with a window frame having a primary pane of glass therein, of means to make the joint between the frame and said primary pane of glass airtight, said means being independent of the means ordinarily used for holding the glass in place, a secondary pane of glass placed against one face of said frame in spaced parallel relation to the primary pane to form a dead air space, a chambered moulding secured to the frame and overlapping the margins of the 55 secondary pane, and a plastic composition in the chamber of the moulding to make an air tight joint between the secondary pane and the frame.

5. The combination with a window frame having a primary pane of glass therein, a chambered 60 moulding secured to the frame and contacting a face of the glass, a plastic composition in the chamber of said moulding to make an air tight joint independently of the means ordinarily used for holding the primary pane of glass in place, 65 a secondary pane of glass placed against one face of said frame in spaced parallel relation to the primary pane to form a dead air space, a chambered moulding secured to the frame and overlapping the margins of the secondary pane, and a plastic composition in the chamber of the moulding to make an air tight joint between the secondary pane and the frame.
